UNITED STATES PATENT OFFICE.

CHARLES E. IRELAND, OF JAMAICA, NEW YORK, ASSIGNOR TO RICH & McLEAN, INC., A CORPORATION OF NEW YORK.

TYPOGRAPHICAL MACHINE.

Application filed June 24, 1926. Serial No. 118,182.

This invention relates to improvements in typographical machines provided with a detachable matrix storage magazine; and the invention has reference, more particularly, 5 to an improved matrix locking device which is mounted on the magazine as a permanent or non-separable fixture thereof.

This invention has for its principal object to provide an improved construction of 10 matrix locking device in the form of a rotatable locking bar which is assembled with the mouth or discharge end of the matrix storage magazine in permanent relation thereto, and which, by simple rotative 15 movement, may be brought into matrix locking or releasing position at will, together with means to secure the bar in either such locking or releasing position; said rotatable locking bar is also provided with a novel 20 means adapted to cooperate with a magazine locking device so as to release the latter for disengagement with the magazine when the locking bar is turned to matrix locking position, and so as to prevent manipulation there- 25 of to unlock the magazine while the locking bar is turned to and positioned in matrix releasing position.

This invention has for a further object to 20 provide such a construction of rotary locking bar, that, when the same is rotated to matrix locking position, it will at the same time lift or retract the stored matrices to remove the weight of the same from the escapement devices of the typographical ma- 25 chine.

Other objects of this invention, not at this time more particularly enumerated, will be clearly understood from the following detailed description of the same.

This invention is clearly illustrated in the accompanying drawings, in which:

Figure 1 is a plan view of the discharge end portion of a matrix storage magazine equipped with the novel rotary matrix locking bar of this invention, and showing the cooperative relation of said locking bar, while in matrix releasing position, with one style of magazine locking latch; Figure 2 is a transverse section, taken on line 2-2 in Figure 1, but showing the cooperative relation of said locking bar, while in matrix locking position, with said magazine locking latch; Figure 3 is a fragmentary vertical cross section, on an enlarged scale, taken 45 through the discharge end of the magazine,

and showing the rotary matrix locking bar in matrix releasing position; Figure 4 is a view similar to that of Figure 3, but showing the rotary matrix locking bar in matrix locking and lifting position; Figure 5 is a detail cross section, on an enlarged scale, taken on line 5-5 in Figure 1; Figure 6 is an end view, on an enlarged scale, of the cam member of the rotary matrix locking bar which cooperates with the magazine locking latch; Figure 7 is a fragmentary plan view, on an enlarged scale, of a modified means for selectively retaining the matrix locking bar in either its matrix releasing or locking position; and Figure 8 is a fragmentary plan view of another style of magazine locking latch with which the rotary matrix locking bar may be cooperatively associated.

Similar characters of reference are employed in the above described views to indicate corresponding parts.

Referring now to said drawings, the reference character 10 indicates a matrix storage magazine, in the upper and lower 80 walls of which are provided opposing guide grooves 11, in which the ears 12 of the matrices 13 are engaged; each pair of opposed grooves 11 supporting a column of matrices 13 for downward feeding movement through and discharge from the magazine under the control of the usual escapement devices 14.

The upper wall of the magazine terminates in a cover plate 15 which borders the discharge end thereof. Said cover plate possesses on its outer side, a transverse boss or enlargement 16. The under side portion of said cover plate, in alignment with its boss or enlargement, is transversely bored to provide a bearing seat 17 for a rotary matrix locking bar 18. Said locking bar 18 is thus mounted for rotation on its longitudinal axis, so that proper turning movements thereof will selectively position the same 95 in either matrix releasing or locking position. That portion of the rotary locking bar 18 which extends across the series of matrix guide grooves 11 of the upper wall of the magazine, is cut away to provide a flat face 100 forming a matrix engaging abutment 19, which is shiftable, by rotation of the locking bar, either into substantially horizontal or substantially vertical plane relative to the plane of the magazine. When the locking 110

bar 18 is turned in one direction, viz, from left to right, said abutment 19 is shifted to substantially horizontal plane, so as to lie substantially flush with the bottoms of the 5 upper guide grooves 11, thus being removed from the path of movement of the upper matrix ears through said upper guide grooves 11, so that the matrices of each column or train thereof are free for dis- 10 charge from the magazine under the control of the escapement devices 14, as shown in Figure 3. When the locking bar 18 is turned in the opposite direction, viz, from right to left, said abutment 19 is shifted to 15 substantially vertical plane, so that one marginal edge portion thereof is projected downwardly across the upper guide grooves 11 and into the path of movement of the upper matrix ears through the latter, so that the 20 rearward upper ears of the lowermost matrix of each column thereof will be engaged by said abutment 19 and discharge or outward movement thereof from the magazine will be positively arrested, as shown in 25 Figure 4.

The position of the rotary locking bar 18 relative to the escapement devices 14, when the magazine is operatively mounted on a linotype machine, and the degree of turning 30 movement imparted to the locking bar, when moving the same to matrix locking position, is such that, not only will the abutment 19 be projected into the above described matrix locking or arresting position, but will also 35 in moving to such position exert an upward or inward moving pressure on the lowermost matrix of each column thereof, whereby the matrices are disengaged from the escapement devices 14, thus removing the weight 40 of the columns of matrices from the latter devices, and thereby obviating any risk of injury to the escapement devices when placing the magazine into service position or removing the same therefrom. This mode 45 of operation is clearly indicated in Figure 4. When the locking bar is turned to matrix releasing position, the abutment 19, in moving away from the upper ears of the 50 lowermost matrices, allows each column of the latter to slide downward until said lowermost matrices are brought into operative relation to the pawls of said escapement devices.

From the above description and an inspection 55 of the accompanying drawings, it will be clearly apparent that the novel rotary matrix locking bar is mounted in connection with the magazine as a permanent or non-separable part thereof. This is of 60 decided advantage, as compared with the heretofore known slidably removable matrix locking bar commonly used in the matrix storage magazines of typographical machines, since it is not, as is the latter, subject to loss or accidental distortion by re-

moval from the magazine. Not only is the above advantage gained by the locking bar of this invention, but due to the novel rotary mode of operation to which it is adapted, great simplicity of construction is attained coupled with ease of manipulation; and, furthermore, the rotary movement of the locking bar carries its abutment 19 into direct upward or inward thrusting engagement with the matrices to which the columns thereof readily yield, thereby obviating all lateral strains or stresses tending to distort or bend the matrix bodies or their ears, which is the common accompaniment of longitudinally shiftable locking bars provided with matrix lifting cam portions or the like operating with sidewise sliding effect relative to the matrices.

Means are provided on an external end 85 of the rotary locking bar 18 both to manipulate it for turning movement, and to retain the same in its respective active and inactive positions. In one form, as shown in Figures 1, 2 and 5 of the drawings, this means comprises the following arrangement and construction of parts. The rotary locking-bar 18 is provided, preferably at its right hand end, with a square shank or equivalent portion 20 of reduced cross-section, which in turn is provided with a screw-threaded portion 21 projecting from its free end. Slidably engaged upon said square shank 19, so as to turn with the locking bar 18, is the hub 22 of a knob or finger-piece 23. Extending axially into the interior of said knob and its hub from the outer end thereof is a socket or bore 24. Screwed upon the outer extremity of said threaded portion 21 is a nut 25, and disposed around the shank 20 intermediate the inner end of said socket or bore 24 and said nut 25 is a compression spring 26. Secured to the adjacent end of said cover plate 15 to project toward the annular peripheral portion of the knob or finger-piece 23 is a stop-pin 27. Provided in the inward face of said annular peripheral portion of said knob or finger-piece 23 are a pair of spaced stop sockets 28 and 29 in which the free end of said stop-pin 27 may be selectively engaged. Preferably a shallow channel or guide groove 30 extends between said stop sockets 28 and 29. The tension of the spring 26 holds the knob inwardly pressed with one or the other of its stop-sockets 28 and 29 operatively engaged 120 with said stop-pin, to thereby immovably retain the rotary locking bar 18 in either its active matrix locking position or its inactive matrix releasing position, as the case may be. For example, when the knob 23 is turned from left to right to position the locking bar in inactive position, the stop-pin 27 will be engaged in the stop-socket 28, thus immovably retaining the locking bar against accidental displacement from said inactive 125 130

position. When it is desired to turn the locking bar 18 to active matrix locking position, the knob 23 is first drawn outwardly against the tension of the spring 26 to release its stop-socket 28 from operative relation to said stop-pin 27, whereupon the knob may be turned from right to left, thus turning the locking bar 18 to active matrix locking position and registering the stop-socket 29 opposite the stop-pin 27, so that by releasing the knob the spring 26 will bring the former into engagement with the latter, thereby retaining the locking bar against accidental displacement from its aforesaid active matrix locking position.

Referring now to Figure 7 of the drawings, there is illustrated thereby another form of means for retaining the locking bar 18 against displacement from either its active or inactive position, as the case may be. In this latter form the outer end of the locking bar 18 is provided with a knob or finger-piece 31 rigidly affixed thereto and provided with spaced stop-sockets similar in kind and arrangement to those of the above first described construction. Slidably mounted in the adjacent end of said cover-plate 15 is a movable stop-pin 32, normally projected therefrom by a compression spring 33 which thrusts outwardly upon its inner end, in such manner that the outer free end of said stop-pin 32 may be selectively engaged with the proper stop-socket accordingly as it is desired to retain the locking bar in either active or inactive position. Connected with and extending laterally outward from said movable stop-pin 32, through a suitable opening 34 provided in the cover plate boss 16, is a finger-piece 35, by means of which the stop-pin 32 may be retracted and released from the knob 31 when it is desired to manipulate the same in turning the locking bar 18 to active or inactive position, as the case may be.

As heretofore mentioned, this invention also includes means, in connection with the novel rotary matrix locking bar, whereby locking devices for locking the matrix storage magazine into a linotype machine may be controlled in such manner as to prevent removal of the magazine from the machine until said matrix locking bar has been turned to active position to hold the matrices against escape from the magazine while the latter is removed from the machine and during other handling thereof. Magazine locking devices of various kinds are employed. One form of such magazine locking mechanism is illustrated in Figures 1 and 2, the same being of that type which serves both to hold the escapement carrying frame 36 in upwardly lifted operative relation to the magazine, and incidently to also lock the magazine against removal, this type of locking mechanism being of a rela-

tively modern form quite familiar, however, to those skilled in the art. In this construction a pair of laterally swinging arms 37 are connected respectively with opposite sides of said escapement carrying frame 36, and each swinging arm 37 carries a pivotally mounted spring pressed latch 38, which are respectively engageable in locked relation to the respective sides of the magazine 10. Arranged to cooperate with one of said swinging arms 37 is a suitably supported slidable bolt 39, having a nosing 40 operatively engageable with a recess 41 in the side of said swinging arm, so that, when thus engaged, said swinging arm is retained against outward movement permitting the disengagement of its latch 38 from locked relation to the magazine. Operatively related to said bolt 39 is a transversely slidable plate 42 having an oblique cam portion 43 which coacts with a corresponding oblique slot in the body of the bolt, whereby transverse movements of said plate 42 will produce movements of said bolt toward or away from the swinging arm 37 to engage or disengage the nosing of the former from the recess of the latter, as the case may be. Said slidable plate 42 is provided at its inner side with a chamfered nose 44 against the rearward side of which bears a thrust spring 45, which normally holds said slidable plate 42 moved toward the side of the magazine, and thus operates to hold the bolt 39 projected to engage its nosing 40 in the recess 41 of said swinging arm. Said chamfered nose 44 is substantially alined to the axis of the rotary locking bar 18 of a magazine operatively mounted in the typographical machine. Fixed on the left hand end of the rotary locking bar 18 is a cam 46 having a helical face 47 (see Figure 6). When said matrix locking bar 18 is turned to inactive matrix releasing position, the helical cam face 47 overhangs the chamfered nose 44, as shown in Figure 1, thus permitting the spring actuated movement of the slidable plate 42 to dispose the bolt 39 in interlocked relation with the swinging arm 37, when the latter is in operative inwardly swung position to engage its latch 38 with the magazine. It will thus be evident that before the swinging arm 37 and its latch can be released from magazine locking position, the bolt 39 must first be retracted by an outward movement of said slidable plate 42. This result is accomplished by turning the matrix locking bar 18 to active matrix locking position, which movement thereof rotates the cam 46 to move its helical face 47 against the chamfered nose 44 thereby pressing outward the slidable plate 42, and through such movement of the latter retracting the bolt 39. It will thus be apparent that once the matrix locking bar 18 is

turned to active matrix locking position, the swinging arm 37 will be released from the restraint of the bolt 39, so that it may be swung outward to remove its latch 38 from locked relation to the magazine, and consequently upon release of the opposite latch also, the magazine may be removed from the machine, it being thus assured that the matrices contained therein are safely secured against accidental outpouring or discharge therefrom, when the same is removed from and handled outside of the typographical machine.

In some older types of typographical machines, the magazines must first be lifted away from the escapement devices before it can be removed from the machine, and to this end the magazine is supported on a pivoted frame, which is upwardly swung by rotary cams 48 actuated by levers 49, generally indicated in Figure 8 of the drawings, and in a manner familiar to those skilled in the art. In this type of machine the cams 48 are locked against actuation, to thus prevent the raising of the magazine to a position freed from the escapement, and therefore subject to removal, by means of a spring pressed pivoted latch 50, mounted on one end of a fixed escapement carrying bar 51, which latch 50 engages a stop-projection 52 on the side of the adjacent cam 48. The tail portion of said pivoted latch 50 is provided with a chamfered nose 53 which is substantially aligned to the axis of the rotary matrix locking bar 18, so that, when the magazine is engaged in operative position in the machine, and said rotary matrix locking bar is turned to inactive matrix releasing position, the helical cam face 47 of the cam 46 of the latter overhangs said chamfered nose 53. It will thus be evident that before the magazine can be raised to removing position, the latch 50 must be swung out of obstructing relation to the stop-projection 52. This result is accomplished by turning the matrix locking bar 18 to active matrix locking position, which movement rotates the helical face 47 of the cam 46 against the chamfered nose of the latch 50 to thereby turn the latter on its pivot or fulcrum to released relation to said stop-projection 52. It will thus be apparent that the cams 48 will be released for actuation whereby the magazine may be raised to removable position, it being at the same time assured that the matrices contained therein are safely secured against accidental outpouring or discharge therefrom, when the same is removed from and handled outside of the machine.

It will be obvious that various changes may be made in the general arrangements and combinations of parts making up the instant invention within the scope of the appended claims. Hence, I do not limit myself to the exact arrangements and combina-

tions of the various devices and parts as above described in the foregoing specification, nor to the exact details thereof as illustrated in the accompanying drawings, except as may be required by the limitations 70 specified in the appended claims.

I claim:—

1. A matrix storage magazine for typographical machines having a rotatable matrix locking bar eccentrically mounted relative to the path of movement of the stored matrices and formed to provide an abutment movable by its rotation into or out of the path of movement of said stored matrices, external means connected with one end of said bar for hand manipulating the same, and means cooperative with said manipulating means for selectively retaining said bar in active or inactive position.

2. In a typographical machine, a removable matrix storage magazine having a rotatable matrix locking bar provided with a portion movable by rotation of said bar into or out of the path of movement of the matrices stored therein, means to hold said magazine against removal from said machine, means to lock said holding means against manipulation, and external cam means axially related to and connected with one end of said matrix locking bar to impinge upon said holding means lock for releasing the same when said matrix locking bar is rotated to active position.

3. In a typographical machine, a removable matrix storage magazine having a rotatable matrix locking bar provided with a portion movable by rotation of said bar into or out of the path of movement of the matrices stored therein, means to hold said magazine against removal from said machine, means to lock said holding means against manipulation, external cam means axially related to and connected with one end of said matrix locking bar to impinge upon said holding means lock for releasing the same when said matrix locking bar is rotated to active position, external means connected with the opposite end of said matrix locking bar for hand manipulating the same, and means cooperative with said manipulating means for selectively retaining said bar in active or inactive position.

4. A matrix storage magazine for typographical machines provided with a rotatable matrix locking bar, a matrix engaging abutment on said bar movable by the rotation of said bar into or out of the path of movement of the stored matrices, an external knob on one end of said bar for rotating the same, and means selectively engageable with said knob to secure said bar in either active or inactive position after rotation by said knob.

5. A matrix storage magazine for typographical machines provided with a rotat-

able matrix locking bar, a matrix engaging abutment on said bar movable by the rotation of said bar into or out of the path of movement of the stored matrices, an external 5 knob slidably mounted on one end of said bar for rotating the same, a fixed stop on said magazine adjacent to said knob, said knob having selective means to engage with said stop to selectively secure the knob and

bar against rotation when the latter has 10 been turned to either active or inactive position, and means for yieldably retaining said knob in engagement with said stop.

In testimony, that I claim the invention set forth above I have hereunto set my hand this 14th day of May, 1926.

CHARLES E. IRELAND.
